RING TAB FOR A TEAR STRIP OPENER

Francis M. Silver, Dayton, Ohio, assignor, by mesne
assignments, to Ermal C. Fraze, Dayton, Ohio

Filed Mar. 23, 1967, Ser. No. 6,344

Term of patent 14 years

(Cl. D58—26)

FIG. 1 is a top plan view of a ring tab for a tear strip opener showing my new design;

FIG. 2 is a bottom plan view thereof;

FIG. 3 is a side elevational view thereof;

FIG. 4 is an end elevational view thereof taken from the bottom of FIG. 1; and

FIG. 5 is an end elevational view thereof taken from the top of FIG. 1.

I claim:

The ornamental design for a ring tab for a tear strip opener, substantially as shown.
